UNITED STATES PATENT OFFICE.

HARRY SPURLING, OF TAYLORVILLE, ILLINOIS.

EAR-TAG TONGS.

1,320,427.

Specification of Letters Patent.

Patented Nov. 4, 1919.

Application filed April 26, 1919. Serial No. 292,801.

To all whom it may concern:

Be it known that I, HARRY SPURLING, a citizen of the United States, and a resident of Taylorville, in the county of Christian 5 and State of Illinois, have invented certain new and useful Improvements in Ear-Tag Tongs, of which the following is a specification.

This invention relates to an improvement 10 in tongs, or tag fastening tools, and more particularly to that class of tools used for setting wire fasteners and the like.

The principal object of the invention is to provide an improved device for setting 15 tags or labels in the ears of swine and the like, the device being designed particularly for use in connection with the identification tag described in a separate application.

The invention resides particularly in 20 providing a clamp which will hold the tag in position to engage the ear of the animal, and which will in one operation effect the piercing of the ear by the prong of the tag, and the crimping of the prong about the 25 eye of the tag, whereby to secure the tag in place on the ear.

A further object of the invention is to provide a device of this class which will be extremely simple, durable and efficient in 30 operation, and inexpensive to manufacture.

With these and other objects in view, which will become apparent as the description proceeds, the invention resides in the construction combination and arrangements of parts hereinafter more fully described and claimed and illustrated in the accompanying drawing in which like characters of reference indicate like parts throughout the several figures, of which:

40 Figure 1 represents a side elevational view of the tool, showing the position of the tag ready to be attached to the ear of the animal,

Fig. 2 represents a similar view showing 45 the position of the tag when finally attached in place and before removal of the tool,

Fig. 3 is a detail sectional view of the 50 lower jaw of the tool taken transversely thereof.

Referring more particularly to the drawing, the tool includes a pair of handles 1 and 2, having offset jaws 3 and 4 respectively, the handle members 1 being pivoted 55 together as at 5. Between the upper jaw 4 and the lower jaw 3, the identification tag

or label 6 is supported. This label includes a resilient substantially U-shaped fastening member comprising upper and lower arms, which are adapted to fit above and below 60 the ear of the animal to which the tag or label is to be secured, it being understood that in securing the label in place the U-shaped fastener is simply fitted or passed over the edge of the ear of the animal, the 65 arms brought toward each other whereby to pierce the ear of the animal and to effect the fastening of the arms together, as will be hereinafter set out. The prong 7 formed at the free end of the upper arm of the tag, 70 pierces the ear, and has its lower or pointed end bent around the eye 8 formed on the lower arm.

The jaws 3 and 4 are so proportioned as to receive the fastening device between them, 75 as indicated in Fig. 1, when the device is in open position. The outer end of the lower jaw 3 is provided with a substantially semi-cylindrical seat 9 into which the eye 8 of the fastener is fitted. The extremity of the upper jaw 4 is provided with a seat having a slot or U-shaped recess 10 into which the bent portion 11 of the upper arm of the fastener, that is, that portion connecting the prong 7 with the arm, is fitted. The seat 9 and recess 11 holds the fastener in position 80 between the jaws of the tool which may be manipulated by one hand in such manner as to engage the fastener over the edge of the ear of the animal. The handles 1 and 2 may 85 then be brought together. This operation will move the arms of the fastening device toward each other, piercing the ear of the animal, and projecting the point 12 of the prong through the eye 8 of the arm. 95

In order to effect the crimping of the prong about the eye, a substantially U-shaped guide slot 13 is provided in the seat 8, and extends from a point concentric with the seat, to a point beyond the periphery of 100 the eye. This guide slot is arranged at an angle with respect to the lower arm of the fastener, rather than axially with respect to the arm whereby the crimped end of the prong 7 will not engage the eye at the meeting ends of the latter.

The handles 1 and 2 are provided with stops 14 to limit the inward movement of the jaws, so that there will be no danger of the arms of the fastener being brought so 110 close together as to clamp the ear of the animal between them.

In operation, the tag or label is inserted in the jaws of the tool in the position indicated in Fig. 1. The operator holds the ear of the animal in one hand, and with the other passes the jaws over the edge of the ear, and then brings the handles together.

This operation effects the piercing of the ear and will effect the crimping of the point over the eye. The tool may then be removed 10 and another tag inserted for identifying another animal.

The use of such a tool as I provide makes it extremely simple for one man to secure the identification tag in place, thus doing 15 away with unnecessary labor. With most of the identification tags in common use, it requires the service of at least three men to effectively secure the tags in place.

Although I have described the preferred 20 embodiment of the invention, I may desire to make such changes in the construction, combination and arrangement of parts thereof as do not depart from the spirit of the invention or the scope of the appended 25 claim.

I claim:—

Ear tag tongs comprising a pair of members pivoted in crossed relation and terminating at one end in handles and at the other

end in jaws, thickened portions formed on 30 the confronting faces of the jaws at the free ends thereof and projecting beyond the inner faces of the jaws toward each other, one thickened portion being provided with a slot 35 adapted to receive one end of a substantially V-shaped wire ear tag disposed between the jaws, one end of the tag being formed with a loop and the other end having formed thereon a right angularly extending prong adapted to be passed through an animal's 40 ear and through said loop, the junction of said prong with the body of the tag being engageable within said slot, the other thickened portion being provided with a recess 45 conformingly receiving said loop and being provided with a substantially semi-circular slot extending from the center of said recess and adapted to receive and bend said prong subsequent to its passage through said loop when said jaws are brought together, said 50 thickened portions being engageable with each other whereby to form a stop for preventing pinching of an animal's ear.
